UNITED STATES PATENT OFFICE.

HARVEY FELDMEIER, OF LITTLEFALLS, NEW YORK, ASSIGNOR TO D. H. BURRELL & COMPANY, OF LITTLEFALLS, NEW YORK.

LIQUID-HEATER.

No. 797,190.

Specification of Letters Patent.

Patented Aug. 15, 1905

Application filed May 23, 1904. Serial No. 209,225.

To all whom it may concern:

Be it known that I, HARVEY FELDMEIER, a citizen of the United States, residing at Littlefalls, in the county of Herkimer and State of New York, have invented new and useful Improvements in Liquid-Heaters, of which the following is a specification.

This invention relates to that class of regenerative liquid-heaters in which the incoming cold liquid and the outgoing heated liquid move in opposite directions on opposite sides of a heat-exchanging wall or partition, through which the cold and heated currents equalize their temperatures to a certain extent, so that the incoming cold liquid absorbs heat from the outgoing heated liquid and cools the latter.

One object of the invention is to render the main parts of the apparatus readily separable by mounting the main parts upon independent supports, one of which is a movable truck or carriage, so that the movable part can be readily moved into engagement with the stationary part in assembling the apparatus or away from the stationary part when access is required to the interior of the apparatus for cleaning or other purposes.

Another object of this invention is to construct the regenerative and the direct heating-surfaces in such manner that they are highly efficient and at the same time simple in construction, the direct heating-surfaces being for these purposes located inside of the rotary partition and the latter being corrugated.

In the accompanying drawings, consisting of three sheets, Figure 1 is a front end elevation of a liquid-heater embodying the invention. Fig. 2 is a vertical sectional elevation thereof. Fig. 3 is a diagrammatic sectional elevation showing the flow-passages and the direction of flow. Fig. 4 is a side elevation, on a reduced scale, showing the movable part of the heater separated from the stationary part.

Like letters of reference refer to like parts in the several figures.

The apparatus consists in the main features by which the flow-passages are formed of an inclosing casing A, having an annular depression a, a core section or part B, having an annular core or projection b, which extends into the depression a and is arranged to leave a flow-space between the annular walls

of these parts, and an annular heat-exchanging partition C, which is arranged in said flow-space about midway between the walls thereof and which has the inlet D for the cold liquid arranged on one side and the outlet E for the heated liquid in the vicinity of the inlet, but on the opposite side, so that the liquid passes from the inlet D backwardly along one side of said heat-exchanging partition C to the bottom c² thereof, then forwardly, but still on the same side of the partition, to the edge c⁴ thereof, then around the edge, then backwardly on the opposite side of the partition to the bottom thereof, and then forwardly to the outlet E, as indicated by the arrows in Figs. 2 and 3.

The casing A is the stationary part of the apparatus and comprises a rear head a', an annular front frame or ring a², both provided with supporting legs or standards a³, and a connecting shell or body a⁴, having in its face the annular depression a, which is formed between the inner and outer annular walls a⁵ a⁶ of the shell. The front end of the outer wall a⁶ is secured to the front ring a², and this outer wall is preferably surrounded by a jacket a⁸, which is secured to the rear head and front ring of the casing and forms a surrounding air or non-conducting space e for the shell or body.

The central portion a⁷ of the shell is secured to the front end of a bearing-sleeve F, which is secured to and projects forwardly from the rear head a'. The central portion of the shell is preferably bolted between a flange f on the front end of the bearing-sleeve and a flange on a bushing f', arranged in the sleeve.

The core-section B is the movable part of the apparatus and is provided with a front head b', which closes the front end of the stationary casing A and carries the hollow annular core b, which projects into the annular depression a of the inclosing shell. The inner and outer walls b² b³ of this core are spaced from and substantially parallel with the corresponding walls a⁵ a⁶ of the shell. The front head is provided with an enlarged central portion or flow-chamber b⁴, which is surrounded by the base of the core and provided with the inlet-nipple D, to which the inlet-pipe d is connected.

The outer annular wall b³ of the core b is provided within the core with the annular heating-chamber G, which extends from the base

or the front end of the core toward the rear end or ridge thereof and forms a direct heating-surface in the outer annular wall of the core. This chamber is supplied with a suitable heating medium, preferably steam, by a pipe g and discharges the condensation by a pipe g' .

The front head b' of the core-section is removably secured to the front ring a^2 of the casing by suitable fastening devices, preferably, as shown, by levers H , arranged radially on the front head, with their outer ends passing through loops h on the head and engaging in holes in forwardly-projecting ears or lugs h' on the front ring of the stationary casing, while their inner slotted ends engage over stationary screws h^2 , projecting from the front head and provided with thumb-nuts h^3 . By turning the thumb-nuts the inner ends of the levers are forced rearwardly, and as their outer ends are confined in the lugs on the front ring they bear on the front head and force the latter tightly against the front ring of the casing. A tight joint is formed between the front head b' and the front ring a^2 of the casing, preferably by a packing-ring i , which is confined in an annular groove in the front head and against which the front ring of the shell bears. Any other suitable fastening and packing devices may, however, be employed in place of those described, and the described details of the casing and core-section may also be varied in other respects.

The heat-interchanging partition C is shaped to correspond with the flow-space between the casing and the core-section and comprises in the construction shown in the drawings curved inner and outer annular portions $c c'$, a curved bottom c^2 , located, respectively, between the corresponding walls of the casing and core, and a front central portion c^3 , the partition having approximately the form of a deep annular trough. The concentric portions $c c'$ of the partition are preferably corrugated in a circumferential direction to increase the area of its surfaces and to give the partition a better hold upon the liquid in rotating, while greatly strengthening the partition, thereby rendering the partition more effective in imparting rotary motion to the liquid and reducing the liability of the liquid to coat the hot surfaces. This partition is secured to the inner end of a rotary shaft K , which passes through the bearing-sleeve F and is journaled in the front bushing f' therein and in a rear bushing f^2 . The shaft is provided at its rear end with tight and loose pulleys $h h'$ or other driving means. The front end of the shaft projects into the central flow-chamber b^4 of the front head. The partition is detachably secured to the front end of the shaft, preferably by a hub L , having a tapering bore which is forced and securely held on the tapering portion of the shaft by a hand-wheel or nut l , screwed on the threaded

end of the shaft. The hub of the partition is preferably provided with handles l' , by which it can be readily manipulated.

The removable core-section is supported by a wheeled truck M of any suitable construction, which, as shown, is provided at its front end with standards m , braced and bolted or otherwise secured to the front head b' of the core. The truck is provided with a handle m' , by which it can be moved to insert the core into the casing or withdraw it therefrom. Tracks m^2 are preferably provided for the truck-wheels to insure the proper position of the core in the casing and prevent injury to the parts in moving the core-section. The latter can be readily removed from the stationary casing with little exertion by simply disconnecting the steam-supply pipe, releasing the fastening devices connecting the front head and casing, and pulling the truck away from the casing. After the core is withdrawn the partition can be detached from its supporting-shaft by unscrewing the hand-wheel and can be removed from the shell or body of the casing. Thus all of the surfaces with which the liquid comes in contact are exposed and can be thoroughly cleaned with little trouble. Neither the core nor the stationary casing need be lifted, and no cumbersome and unwieldy apparatus is required to remove the core.

In the operation of the apparatus the liquid to be heated enters the central portion of the apparatus through the supply-orifice D and passes first into the flow-chamber b^4 , then rearwardly between the inner concentric portion c of the rotary partition and the inner wall b^2 of the core, then forwardly between the outer wall b^3 of the core and the outer or peripheral portion c' of the partition and is heated to its highest temperature by passing over the direct heating-surface. The heated liquid then passes around the edge c^4 of the peripheral portion c' of the partition, then rearwardly between the peripheral portion of the partition and the outer wall a^6 of the stationary shell of the casing, and then forwardly between the inner portion c of the partition and the inner wall a^5 of the shell to the discharge-pipe R' , through which it leaves the beater. The liquid is kept in rapid motion in the flow-space by the rotation of the partition, whereby the liquid is prevented from adhering to and coating the heated surfaces, and this effect is enhanced by the corrugations of the partition. The cold incoming and the heated outgoing liquid-currents move in opposite directions on opposite sides of the partition, which causes an exchange of heat between the currents, resulting in heating the cool incoming liquid and cooling the heated outgoing liquid. The temperature of the liquid is thus first raised by absorbing heat from the outgoing liquid until the direct heating-surface is reached, then raised to the desired degree on the direct

heating-surface, and then lowered considerably before leaving the heater, whereby a large saving in heat is effected. The steam-chamber being arranged in the outer portion of the base of the core and surrounded by the flow-passages, the peripheral portion of the rotary partition and the outer portion of the outer casing is protected thereby to a large extent against radiation and loss of heat.

While the casing is described as stationary and the core-section as carried by the truck, an obvious reversal of the parts would be to mount the casing on the truck and the core-section on a stationary support.

The apparatus is especially suitable for heating or pasteurizing milk, but may be used for treating other liquids, and can also, with but slight changes, be employed for cooling liquids.

The flow-space is provided with any well-known or suitable air-vent for permitting the escape of the air when the milk or other liquid to be treated is first admitted to the flow-space.

I claim as my invention—

1. The combination of a stationary, horizontally-disposed casing having an open upright end, a horizontally-movable core which projects into the open end of said casing and is separated therefrom by a flow-space, a horizontally-movable truck or carriage on which said core is supported, means for circulating liquid through said flow-space, and means for changing the temperature of the liquid, substantially as set forth.

2. The combination of a stationary, horizontally-disposed casing having an open upright end, a horizontally-movable core which projects into the open end of said casing and is separated therefrom by a flow-space, a horizontally-movable truck or carriage on which said core is supported, means for circulating the liquid through said flow-space, means for heating the liquid, and a rotary partition arranged in said flow-space between the casing and the core, substantially as set forth.

3. The combination of a stationary, horizontally-disposed casing having an open upright end, a horizontally-movable core which projects into the open end of said casing and is separated therefrom by a flow-space, a horizontally-movable truck or carriage on which said core is supported, a rotary partition detachably mounted on said stationary casing and removable therefrom when said core is removed, means for supplying liquid to said flow-space on one side of said partition and discharging it therefrom on the other side of the partition, and means for changing the temperature of the liquid, substantially as set forth.

4. The combination of a stationary, horizontally-disposed casing having an open upright end, a horizontally-movable truck or casing, a horizontally-disposed core which is secured

to said truck or carriage and projects into the open end of said casing and is separated therefrom by a flow-space, a rotary shaft journaled in said casing, a partition detachably secured to said shaft and arranged in said flow-space between the casing and the core, means for supplying liquid to said flow-space on one side of said partition and discharging it therefrom on the other side, and a heating-chamber in said core, substantially as set forth.

5. The combination of a stationary, horizontally-disposed casing having an open upright end, a horizontally-movable truck or carriage, a removable head for said casing mounted on said truck, means for fastening said head to the open end of said casing, a core which is secured to said head and projects into said casing and is separated therefrom by a flow-space, a rotary heat-interchanging partition arranged in said flow-space between the casing and the core, means for circulating liquid through said flow-space, and means for heating the liquid, substantially as set forth.

6. The combination of a stationary, horizontally-disposed casing provided with an annular depression in its open end, a head which closes the open end of the casing and is detachably secured thereto, an annular core secured to said head and projecting into said depression, from which it is separated by a flow-space, a heating-chamber forming part of said core, a truck or carriage which is movable toward and from said casing and on which said head is mounted, a rotary partition arranged in said flow-space, a rotary shaft which is journaled centrally in said casing and to which said partition is detachably secured, and liquid-circulating pipes communicating, respectively, with said head within the core and with said casing within said depression, substantially as set forth.

7. The combination of a stationary, horizontally-disposed casing provided with an annular depression in its open end, a detachable head which closes the open end of the casing and is provided with a central flow-chamber, an annular core arranged on said head around said chamber and projecting into the depression of the casing, from which it is separated by a flow-space, a rotary shaft journaled centrally in said casing and projecting into said flow-chamber, a rotary partition detachably secured to said shaft in said flow-chamber and extending therefrom through the flow-space between the core and the casing, an inlet and an outlet for the liquid on opposite sides of the partition, and means for changing the temperature of the liquid, substantially as set forth.

8. The combination of an inclosing casing having an annular depression in its open end, an annular core projecting into said depression and separated therefrom by a flow-space, a rotary partition having the form of an annular trough arranged in said flow-space and

having its outer portion arranged outside of said core, a heating-chamber arranged in the outer portion of said core and forming a direct heating-surface adjacent to and inside of the free end of said rotary partition, and means for circulating liquid through said flow-space, substantially as set forth.

9. The combination of a stationary, horizontally-disposed casing provided with an annular depression in its open end, a detachable head which closes the open end of the casing and is provided with a central flow-chamber, an annular core arranged on said head around said chamber and projecting into the depression of the casing, from which it is separated by a flow-space, a rotary shaft journaled centrally in said casing, a rotary partition secured to said shaft and extending from said shaft through the flow-space between the core and the casing, an annular heating-chamber arranged in the outer portion of the base of the core and forming a direct heating-surface inside of the peripheral portion of the rotary partition, and means for circulating liquid through the flow-space, substantially as set forth.

10. The combination of an inclosing annular casing, an annular core projecting into said casing and separated therefrom by a flow-space, and a rotary heat-interchanging partition arranged in said flow-space between said casing and said core and having its concentric portion provided with corrugations, substantially as set forth.

11. The combination of an inclosing casing having an annular depression in its open end, an annular core projecting into said depre-

sion and separated from the casing by a flow-space, a rotary partition arranged in said flow-space and having its concentric portions provided with corrugations, an inlet and an outlet for the liquid on opposite sides of said partition, and means for changing the temperature of the liquid, substantially as set forth.

12. The combination of an inclosing casing having an annular depression in its open end, an annular core projecting into said depression and separated therefrom by a flow-space, a rotary partition arranged in said flow-space, said partition extending from its hub backwardly between the inner concentric walls of the depression and core and then forwardly between the outer walls of the depression and core and having its concentric portions corrugated, an inlet and an outlet for the liquid on opposite sides of the partition, and a heating-chamber arranged in said core and forming a direct heating-surface in the outer wall thereof, substantially as set forth.

13. The combination of an annular casing having an internal flow-space for the liquid to be treated, means for changing the temperature of the liquid passing through the flow-space, and a rotary partition arranged in said flow-space and provided with corrugations arranged in a circumferential direction, substantially as set forth.

Witness my hand this 13th day of May, 1904.
